Primary Examiner — Michelle E. Wilson
Assistant Examiner — Clese Moore Jr(57) **CLAIM**

The ornamental design for an oral care implement, as shown and described.

DESCRIPTION

The features of the preferred embodiments will be described with reference to the following drawings, in which:

FIG. 1 is a front perspective view of an oral care implement according to a first embodiment of the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is a front perspective view of an oral care implement according to a second embodiment of the new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is an enlarged top view thereof; and

FIG. 16 is an enlarged bottom view thereof.
